PRESSURE CASTING MACHINES

Leon Saives, Billancourt, France, assignor to Regie Nationale des Usines Renault, Billancourt, France, and Societe des Hauts Fourneaux et Forges d'Allevard, Paris, France, a corporation of the French Republic

Application July 28, 1953, Serial No. 370,837

Claims priority, application France August 30, 1952

3 Claims. (Cl. 22—68)

The invention relates to machines for casting metals and more especially ferrous metals under pressure and is concerned with improvements applied to the moulds, to the ladle cylinder and to the relative arrangement of elements of the machine.

Certain relative arrangements of the main parts forming a pressure moulding machine and also the arrangement of the joining plane of the mould, having particular properties such as the ease with which the articles produced are made, form the subject of the invention.

The improvements provided by the invention for these machines render it possible to obviate certain disadvantages which exist at present.

(a) It is desirable to reduce to the maximum extent the distance traveled by the molten metal between the pouring point and the mould and to facilitate the evacuation of impurities.

(b) At right angles to the pouring hole, the liquid steel reaching the metal wall of the cylinder causes a partial union of the steel with the metal of the cylinder, which impedes the displacement of the piston.

(c) By using moulds having a flat joint, the internal edges of the moulds at the level of the joint are rapidly deformed in a permanent manner because of the temperatures which are reached.

(d) Where the moulded articles have considerable differences in thickness, the cooling of the different parts takes place at unequal speeds, the thick parts being still liquid while the thin parts are solidified. The result is that the withdrawal is carried out to the detriment of the thick parts, with the appearance of cavities in the articles which are known under the name of shrinkage holes.

Novel arrangements in accordance with the invention are shown by way of non-limitative example in the accompanying drawing.

Figures 1 to 4 show diagrammatically several relative positions of the horizontal mould and of the injection cylinder.

Figure 5 shows the refractory lining of a part of the ladle cylinder and the arrangement of protecting guide bars in a cross-sectional view taken along the line 5—5 of Fig. 5A.

Fig. 5A is a longitudinal fragmentary sectional view taken along the line 5A—5A of Fig. 5 and showing in detail the construction of the right-hand portion of the machine shown diagrammatically in Fig. 4.

Figures 6 and 7 shows the arrangement of joints in the moulds.

Figure 8 shows a mould with a staggered joint.

Figure 9 represents a mould with cooling means.

(a) Arrangement of the main parts forming a machine for casting under pressure:

In the arrangement shown in Figure 1, the mould comprises two half sections 1 and 2: The plane of the joint 3 is horizontal. The injection cylinder 4 is at the same time a ladle cylinder and contains an injection piston 6 and a closing piston 5. The injection cylinder 4 is vertically above the mould.

2

With such an arrangement, the length of the path of the molten metal is greatly reduced. On the other hand, the slag which has a tendency to appear remains in the channel.

5 In the arrangement according to Figure 2, the mould comprises two half sections 1a and 2a: The plane of the joint 3a is horizontal. The injection cylinder 4a is at the same time a ladle cylinder and contains an injection piston 6a and a closing piston 5a. The injection cylinder 4a is disposed horizontally below the mould 1a and 2a. This arrangement renders it possible to provide an injection cylinder which can be made in two parts and can be opened, this facilitating the cleaning thereof.

By reference to Figure 3, it will be seen that the mould 15 comprises two half sections 1b and 2b. The joint plane 3b is horizontal. The cylinder 4b, disposed horizontally along the joint plane, serves at the same time as a ladle cylinder and injection cylinder. The piston 6b is the injector piston. With such an arrangement, the path of 20 the molten metal is very restricted and the injection cylinder may be arranged to open into two parts, which facilitates the cleaning thereof.

In the arrangement according to Figure 4, the joint plane 3c of the mould consisting of two half sections 1c and 2c is horizontal, and the injection cylinder 4c is disposed vertically beneath the mould. The liquid metal is injected by the piston 6c. The metal is poured into the ladle cylinder 7 and moved by the piston 8. The ladle cylinder may be designed so as to open into two parts 30 for facilitating the cleaning thereof.

(b) Protection obtained by refractory half shells lining the injection or ladle cylinders and ladle guide bars in a pressure casting machine:

In order to avoid deterioration of the ladle cylinder at 35 right angles to the pouring hole, a refractory lining or "Ceramet" lining is disposed in the lower portion of the cylinder at the point of impact of the molten metal from the cylinder. On either side of this lining, each of its upper generatrices has arranged thereon a metal guide bar and the contact joint is disposed between these bars and the upper steel half shell. This arrangement avoids the wear which would be produced on the edge of a joint which is formed of plain refractory material.

Figure 5 is a transverse section of such a device applied 45 to the ladle cylinder of a machine in which this cylinder, by way of example, has a horizontal axis. The ladle cylinder, formed of an upper half shell 11 and a lower half shell 9, is surmounted by the pouring hole 12. Metal guide bars 10 protect the edges 16 and 17 of the lower 50 refractory half shell 9 supported in the other half 11' of the ladle cylinder. The metal plates 10 and 10' are secured to their respective cylinder halves by fastening means such as screws disposed in the screw holes 26 and 27, respectively, the upper plates 10' engaging upper lining 25.

During the casting, the molten metal can obviously not 55 attack the refractory materials and is sufficiently cooled on arriving at right angles to the metal of the cylinder in order not to be able to cause the partial fusion of the cylinder.

(c) Mould arrangement intended for casting under pressure with staggered points:

In order to avoid the deterioration, there is employed 60 a special arrangement of the joint plane of the moulds which is known as a "staggered joint."

Figure 6 is a sectional elevation of a mould having a 65 staggered joint (two parts 20 and 21).

Figure 7 shows a modification of the previous arrangement in which the parts are inverted and are designated 70 20a and 21a, respectively.

Figure 8 shows a mould with a staggered joint (two parts 20b and 21b) for an object having a core 22b.

In the mould having a staggered joint, the metal of the edges is subjected to much smaller thermal stresses. The same mould may thus withstand a much larger number of operations.

(d) Use of cooling devices in the moulds:

In order to overcome the disadvantages of cooling at different speeds in moulded articles having unequal sections, the invention here has for its object the novel application of cooling devices to the casting of ferrous metals under pressure, said cooling devices being in the form of members introduced beforehand into the mould and having in this case novel advantages.

Figure 9 shows by way of example a mould permitting the formation of a casting under pressure with the use of cooling devices. 20c and 21c are the half sections of the mould and 22c is a cooling core.

The cooling devices may be so designed as to remain embedded in the articles by providing, for example, a suitable external covering.

As the casting obtained under pressure are extremely smooth, it is easy to withdraw a cooling device from a casting formed under pressure. This property renders it possible to use the cooling devices as cores and thus to obtain directly, during the casting, holes of any suitable shape capable of remaining rough cast.

The present invention obviously covers the application of all types of cooling devices to all forms of castings obtained under pressure from ferrous metals.

I claim:

1. A machine for casting ferrous metals and the like under pressure comprising, in combination, a vertically-extending injection cylinder and a horizontally-disposed ladle cylinder connected to said injection cylinder, said ladle cylinder having a casting opening and being formed from two semi-cylindrical portions with the lower portion comprising opposite the casting opening a refractory

lining, the joint between said semi-cylindrical cylinder portions being provided by metallic bars whereby said cylinder portions are separated by said bars.

2. A machine for casting ferrous metals and the like under pressure comprising, in combination, an injection cylinder and a ladle cylinder combined with said injection cylinder in a single body, said body having a casting opening and being formed from two semi-cylindrical portions with the lower portion comprising opposite the casting opening a refractory lining, the joint between said semi-cylindrical cylinder portions being provided by metallic bars whereby said cylinder portions are separated by said bars.

3. A machine for casting ferrous metals and the like under pressure comprising, in combination, an injection cylinder and a ladle cylinder combined with said injection cylinder in a single body, said body having a casting opening and being formed from two semi-cylindrical portions with the lower portion comprising opposite the casting opening a refractory lining, the joint between said semi-cylindrical cylinder portions being provided by metallic bars whereby said cylinder portions are separated by said bars, said machine including a casting mould and said body being horizontally disposed and being positioned below the casting mould and having a removable end in the form of a piston.
